RING

Edwin M. Lovell, Topeka, Kans.

Application September 6, 1938, Serial No. 228,655

3 Claims.

(Cl. 63—15)

My invention relates to finger ring constructions and has as one of the principal objects thereof the provision of a combination ring construction wherein two rings, such as a wedding ring and an engagement ring, while separate and separable units are so fashioned that they will interlock, one with the other, in substantially a single unit when worn together upon the finger.

Another object of my invention is to provide 10 a ring construction of the character described equipped with means for interlocking said rings together in a manner to preclude relative axial and rotary movement of said rings.

A further object of my invention is to provide 15 a ring construction of the character described wherein the mounting of one ring fits within the mounting of the other ring and coacts therewith to simulate a unitary ring construction.

A still further object of my invention is to provide 20 a ring construction of the character described capable of being readily assembled and disassembled and which is economical in manufacture.

Other objects and advantages will be apparent 25 from the following description, appended claims and annexed drawing.

Referring to the drawing wherein like reference characters designate like parts throughout the several views:

30 Figure 1 is a top plan view of my invention.

Figure 2 is an end elevation thereof.

Figure 3 is a sectional view taken on the line 3—3 of Figure 2.

Figure 4 is a sectional view taken on the line 35 4—4 of Figure 3.

Figure 5 is a disassembled perspective view of the respective rings.

Figure 6 is an end elevation of a modified form of my invention.

40 Figure 7 is a disassembled top plan view of said modified form.

In practicing my invention, in the preferred embodiment illustrated in Figures 1 to 5 inclusive of the drawing, I provide a pair of rings adapted 45 for interlocking connection with each other to form a single unit. One of said rings constitutes a wedding ring 5 and the other ring an engagement ring 6.

The wedding ring 5 comprises a band 7 defining 50 a finger opening 7a and is fashioned on the outer periphery thereof with a relatively thick wide and elongated mounting 8 formed with a substantially ovate shaped opening 9 extending therethrough and providing a pair of spaced 55 under faces 10 and 11 integrally connected to the

band at the ends thereof. The under face 10 extends laterally a greater distance on one side of the band 7 than the under face 11 and is undercut on each end thereof to form a pair of oppositely disposed seats and rib sections 12 and 13 respectively.

The ends of the rib sections at the jointures with the band are formed with notches 14 for a purpose hereinafter set forth.

The engagement ring 6 comprises a band 15 defining a finger opening 15a and is formed on the outer periphery thereof with a mounting 16 provided with upper and lower faces 17 and 18 respectively, said upper face being equipped with stone settings 19 of an ordinary character. The 15 mounting 16 is of a substantially ovate configuration fitting within the opening 9 of the ring 5 and the underface 18 of said mounting is contiguous with the inner peripheral face of the band 15 whereby to effect registry of the finger 20 openings 7a and 15a with each other. As in the instance of the mounting 8, the underface 18 extends a greater distance on one side of the band 15 than the other and opposite to that of the under face 10 of the mounting 8.

The ends of the band 15, adjacent the mounting 8 and on their outer peripheral faces thereof, are provided with notches 19' coacting with the notches 14 of the rib sections 13 to effect interfitting therewith. The ends of the band 15, adjacent said notches 19', seat within the seats 12 and thereby interlock the rings 5 and 6 together as a unit and preclude relative axial and rotary movement of said rings. When it is desired to disengage said rings from each other, the mounting 8 is withdrawn downwardly through the opening 9 and by a reverse operation the rings may be readily connected together.

In the modified form illustrated in Figures 6 and 7 the outer face of the band 20 adjacent the mounting 21 is provided with a pair of recesses 22 and the inner face of the offset portion 23 adjacent the mounting 24 of the band 25 is likewise provided with spaced recesses 26 for accommodating therein the recessed portions of the band 20 when the bands are in assembled condition. It will be noted that the mounting 24 of the band 25 differs from the mounting of the band 5 of the preferred embodiment in that 50 said mounting is disposed laterally and only on one side of said band.

It is to be distinctly understood that various changes and modifications may be resorted to in the construction and arrangement of the parts 55

without departing from the spirit of the invention or scope of the appended claims.

Having described my invention, what I claim is:

- 5 1. In a finger ring construction, a pair of abutting ring bands defining registering finger openings, one of said bands fashioned with a mounting formed with an aperture and provided with an underface formed with oppositely disposed seats and notched rib sections, the other of said bands formed with a mounting fitting within said aperture, said last mentioned band adjacent the mounting thereof formed with notches receiving said notched rib sections in a 10 manner to effect seating of said last mentioned band within said seats to preclude relative axial and rotary movement of said bands.
- 15 2. In a finger ring construction, a pair of abutting ring bands defining registering finger openings, one of said bands fashioned with a mounting formed with an aperture and provided with an underface formed with oppositely disposed seats and notched rib sections, the other of said bands formed with a mounting fitting

within said aperture, said last mentioned band adjacent the mounting thereof formed with notches receiving said notched rib sections in a manner to effect seating of said last mentioned band within said seats to preclude relative axial and rotary movement of said bands, said last mentioned mounting equipped with stone settings and coacting with said first mentioned mounting to simulate a unitary ring structure.

- 20 3. In a finger ring construction, a pair of abutting ring bands defining registering finger openings, each of said bands fashioned with oppositely disposed offset sections including one overlying the other, one of said sections fashioned on the inner face thereof with spaced recesses, the other of said sections fashioned on the outer face thereof with spaced recesses coacting with said first mentioned recesses to effect overlying of one section relative to the other and disposing said sections in abutting relation whereby 15 20 said bands are locked together against relative rotative and axial movement.

EDWIN M. LOVELL.
